UNITED STATES PATENT OFFICE

2,103,056

CUT-OUT AND JOINT THEREFOR

Theodore Birkenmaier, St. Louis, Mo., assignor to
 W. N. Matthews Corporation, St. Louis, Mo., a
 corporation of Missouri

Application October 1, 1936, Serial No. 103,523

7 Claims. (Cl. 200—115.5)

This invention relates to cutouts, and with regard to certain more specific features, to fuse cutouts for direct application to line wires and the like.

5 This invention is an improvement upon the apparatus shown in the application of Theodore Birkenmaier, Serial No. 46,494, filed October 24, 1935, for Cutout. Among the several objects of the invention may be noted the provision of a 10 fuse holder which may easily be applied to and removed from a hanger but which, upon normal explosive or analogous operation, will not automatically become removed from said hanger nor fall therefrom; and the provision of apparatus of 15 the class described which is simple in form and operation. Other objects will be in part obvious and in part pointed out hereinafter.

The invention accordingly comprises the elements and combinations of elements, features of 20 construction, and arrangements of parts which will be exemplified in the structures hereinafter described, and the scope of the application of which will be indicated in the following claims.

In the accompanying drawings, in which is 25 illustrated one of various possible embodiments of the invention,

Fig. 1 is a side elevation of the cutout showing the method of applying a fuse holder to its hanger;

30 Fig. 2 is a right end elevation of Fig. 1;

Fig. 3 is a view similar to Fig. 2 showing the hanger alone;

Fig. 4 is a fragmentary vertical section taken on line 4—4 of Fig. 3;

35 Fig. 5 is a lateral section taken along line 5—5 of Fig. 4;

Fig. 6 is a view similar to Fig. 1 but on a reduced scale and showing the fuse holder in final position within its hanger; and,

40 Fig. 7 is a view similar to Fig. 6 showing the process of removing the fuse holder from its hanger.

Similar reference characters indicate corresponding parts throughout the several views of 45 the drawings.

Referring now more particularly to Fig. 1, there is shown at numeral 1 a line wire from which it is desired to suspend the cutout of the present invention. The cutout is made in two parts, 50 namely, a hanger H and a fuse holder F. The fuse holder F is manipulated by means of a lineman's stick S.

The hanger H comprises the C-frame 3 through one side of which is threaded a screw 5. The 55 rear end of said screw is provided with a head

7 having a gudgeon 9 adapted to be engaged by the slotted end 11 of the said stick S. The screw 5 controls a clamp 13 which, with the upper end of the C-frame grips the wire 1 to hold the hanger H on said wire. 5

The lower end of the C-frame 3 has a depending extension 15 carrying at its bottom a socket 17. From the socket extend flaring guide fingers 19.

Pivoted at the upper end of the extensions 15 10 is a latch 21 which is normally biased by a spring 23 (Fig. 4) to a latching position above said socket 17. The amount of bias given to the latch 21 by the spring 23 is limited by a T-shaped extension 25 (Fig. 5) which extends through a 15 slot 27 in the member 15. Thus the latch 21 is normally pressed to the right (Figures 1, 4, and 6). When the latch 21 is in its biased position (Figures 4 and 6), it obstructs the outlet from the socket 17, but when not biased by the spring 23 as shown in Fig. 7, it does not obstruct the 20 outlet.

The fuse carrier comprises an upper contact 29 having a screw cap 31 for fastening the upper end of a fuse link 33. The contact 29 has formed therewith an eye 35 with which cooperates a lug 37 of said head 11 of the stick S. The purpose of this cooperation is to mount the fuse support on the end of the lineman's stick for application and removal to and from the holder H. 30

From the lower end of the contact 29 extends an insulating tube 38, the latter passing through and being held to a lower contact 39. The fuse link 33 extends out from the open lower end of the tube 38 and is held by a spring member 41 which is attached to the lower contact 39, as at 43. A wire holding connector 45 also forms part of the lower contact 39. The character of the spring member 41 has already been described in my Patent 1,935,386, dated November 14, 1933. Its purpose is to withdraw and drop the lower end of the fuse 33, after the fuse blows at its upper reduced portion 47. 35

At the upper end of the contact 29 is a metallic extension 49 which carries a ball 51 adapted to snugly fit into the socket 17 and having formed adjacent its end on one side a flat fin 53. This fin 53 extends around the ball and down to the upper contact 29 and carries an extending portion 55. 40

The operation of the device is as follows:

The lineman initially and permanently applies the holding clamp H to the wire 1 as shown in Figures 1 and 2 and tightens the screw 5. 50

After having placed a fuse in the fuse holder and thus having put the spring 41 into bowed tension (Fig. 1), he fastens connector 45 to slack wire 46. Next he applies the lug 37 of the stick 5 S to the eye 35 as shown. By this means he can lift the fuse support upwardly so as to move the ball 51 approximately along the line of the curved arrow shown in Fig. 1. The extension 49 under these conditions moves in between the guiding fingers 19, the portion 55 functioning as a rudder to keep the ball 51 directed forwardly.

As the ball 51 gravitates toward the socket 17, it engages the lug 57 on the lower end of the latch 21 and forces the latch aside against the 15 bias of the spring 23. The parts then assume the position shown in Fig. 6 wherein the ball 51 is seated in the socket 17 and the latch 21 has sprung back under bias of the spring 23 to trap the ball in its socket. The lineman's stick S 20 may be pulled down as shown in Fig. 6 to firmly seat the ball 51 and may then be removed from the eye 35. The fuse 33 is then in circuit. The wire 46 is of a length now to be straightened out with enough slack to permit of the movement 25 of the ball 51 to and from the socket 17 and to permit the movement illustrated in Fig. 7 (to be further described below).

If the fuse blows, as under heavy overload, the engendered gases are projected expulsively 30 from the lower end of the tube 31, thus causing a reaction along the center line of the cartridge. Hence the fuse holder F as a whole tends to move upwardly. The tendency of ball 51 to move out from the seat 17 is resisted by the then shut latch 35 21.

In order to remove the fuse holder, the lineman's stick S is reapplied as shown at Fig. 7 and the fuse holder pushed upwardly as indicated. Inasmuch as the upward motion of the ball 51 40 is resisted by the latch 21, there is a tendency to rotate the fuse holder as indicated in Fig. 7. The length of the wire 46 is such as to permit this rotation.

The rotation causes the fin 53 to come into 45 contact with the lower lug 57 of the latch 21 to push it aside. This contact also causes a fulcruming of the fuse holder to occur at the lug 57, whereupon the ball is automatically pushed out by the return biasing action of the latch. 50 After complete removal of the fuse holder, the latch 21 is back in the position shown in Fig. 1, ready for the application of another or the same re-fused holder.

Among the advantages of the invention may 55 be noted the following:

(1) The fuse holder is easily separable from the clamp H and therefore the clamping action need not be resorted to in applying and removing new fuses. 60 (2) The loaded fuse holder (connected to one wire at connector 45) is quite easily applied to the clamp merely by placing it on the end of the lineman's stick and dropping the ball 51 into the socket 17, whereupon the latch automatically locks it into position. The lineman need not handle any live connectors. 65

(3) The normal reactions due to blowing of the fuse do not separate the fuse holders from the clamp.

70 (4) The normal action of applying the lineman's stick, as shown in Fig. 7, and merely pushing upwardly, causes the proper rotation for thrusting aside of the latch, fulcruming, and automatic ejection of the ball from the socket. This 75 is done without violent action so that the fuse

holder does not inadvertently drop from the lineman's stick and it may therefore be gently brought to the ground for reloading.

(5) The rudder extension 55 on the fin 53, in connection with the guides 19 prevents the fuse holder from swiveling more than a limited amount and insures that even a merely approximately proper position of application of the holder will result in its finding an ultimately proper seated position. 10

The device has various applications, including use on lightning arresters and transformer connections where quick and easy removal (without the necessity for removing the wire clamp) is important. 15

In view of the above, it will be seen that the several objects of the invention are achieved and other advantageous results attained.

As many changes could be made in carrying out the above constructions without departing 20 from the scope of the invention, it is intended that all matter contained in the above description or shown in the accompanying drawings shall be interpreted as illustrative and not in a limiting sense. 25

I claim:

1. A cutout comprising a clamp adapted to be permanently attached to a line wire, a depending socket on said clamp, a latch associated with said socket, a fuse holder, a fuse therein, 30 a ball extending from said fuse holder and adapted to be engaged with said socket, said latch automatically locking said ball into the socket against normal reaction due to blowing of a fuse in the fuse holder, and means associated with said ball adapted to move the latch to releasing position when said ball is rotated as by manually pushing on the fuse holder. 35

2. A cutout comprising a clamp adapted to be permanently attached to a line wire, a depending socket on said clamp, a latch associated with a socket, a fuse holder, a fuse in the holder, a ball extending from said fuse holder and adapted to be engaged in said socket, said latch automatically locking said ball in the socket against 40 normal reaction due to blowing of a fuse in the fuse holder, and means associated with said ball adapted to move the latch to releasing position when said ball is rotated as by pushing on the fuse holder with a lineman's stick, flaring guide means extending from said socket, and means associated with said fuse holder adapted to coact with said guide means when the ball is applied to the socket to properly position the fuse holder. 45

3. A cutout comprising a line wire clamp, a depending socket, a latch comprising a lever pivoted above the socket and swinging thereacross, means biasing said lever to latching position over the socket, a fuse holder having a circular portion adapted to engage said socket, said circular portion temporarily deflecting said lever against its bias as the portion moves towards the socket, a lug on said lever adjacent said circular portion, and an extension on the circular portion adapted 60 to engage said lug upon rotation of the circular portion by a manual push on the fuse holder, whereby said lever is moved to a position to permit removal of the circular portion under the fulcruming action of said extension on said lug. 65

4. A cutout comprising a line wire clamp, a depending socket, a latch comprising a lever pivoted above the socket and swinging thereacross, means biasing said lever to latching position over the socket, means limiting said bias, a fuse 70

75

holder having a ball adapted to engage said socket, said ball temporarily deflecting said lever against its bias as the ball moves towards the socket, a lock on said lever adjacent the ball, and an extension on the ball adapted to engage said lever upon rotation of the ball by a manual push on the fuse holder, whereby said lever is moved to a position to permit removal of the ball, said ball being removed under the fulcrumming action of said extension on said lug and by the biasing return action of said lever.

5. A joint comprising a socket, a latch pivoted above the socket comprising a lever swinging thereacross, a member adapted to be applied to the socket and to push said lever aside during application, and an extension on the member adapted to engage the latch upon rotation to thrust aside the latch to permit outward movement of the member from the socket.

10 6. A joint comprising a socket, a latch pivoted above the socket comprising a lever swinging thereacross, a member adapted to be applied to the socket and to push said lever aside during application, and an extension on the member

adapted to engage the latch upon rotation to thrust aside the latch to permit outward movement of the member from the socket, biasing means for the lever normally moving it to latching position, and fulcruming means between 5 the lever and said member whereby said member may be moved toward a position when the lever is thrust aside wherein the bias of the lever will automatically further thrust said member away from the socket.

10 7. A joint comprising a member having a socket, a latch pivoted above the socket comprising a lever swinging thereacross, a ball adapted to be applied to the socket and to push said lever aside during application, and a fin on the ball 15 adapted to engage the latch upon rotation of the ball to move the latch to permit outward movement of the ball from the socket, a lug on the end of the lever adapted to fulcrum said fin as the ball is rotated, whereby the ball is fulcrumed from the socket when the latch is in clearing position, and guides adjacent said socket 20 cooperating with the fin.

THEODORE BIRKENMAIER.
